Filed Jan. 6, 1970, Ser. No. 20,785

Term of patent 14 years

Int. Cl. D29—99

U.S. Cl. D72—1

FIG. 1 is a front elevational view of a driveway marker embodying my new design, the ground being shown in broken lines for illustrative purposes only;

FIG. 2 is an enlarged fragmentary front elevational view thereof, the rear being identical to the front;

FIG. 3 is an enlarged fragmentary side elevational view thereof;

FIG. 4 is a sectional view taken on line 4—4 of FIG. 2;

FIG. 5 is a sectional view taken on line 5—5 of FIG. 2;

The faceting of the reflective surfaces of the driveway marker is partially shown in FIGS. 1 and 2 for convenience of illustration and is understood to be continuous over the areas indicated. The standard is fragmentarily shown in FIGS. 2 and 3 for convenience of illustration.

I claim:

The ornamental design for a driveway marker, substantially as shown and described.
